Des. 188,829
Patented Sept. 13, 1960

188,829

BOAT HULL

Henry Donald Canazzi, 178 Jewett Parkway,
Buffalo, N.Y.

Filed Aug. 1, 1958, Ser. No. 52,008

Term of patent 7 years

(Cl. D71—1)

Figures 5 and 6 are sectional views on the lines 5—5 and 6—6, respectively of Fig. 1.

I claim:

The ornamental design for a boat hull, substantially as shown.
